UNITED STATES PATENT OFFICE

2,441,691

GATE LATCH AND OPENER

Chester E. Bole, Vallejo, Calif.

Application March 22, 1947, Serial No. 736,466

10 Claims. (Cl. 292—255)

1

This invention relates to a gate latch or the like and has for one of its objects the provision of a latch that is economical to make, easy to operate, and that is automatically restored to gate holding position after each operation thereof, and which latch includes means for automatically swinging the gate open upon each such operation.

Another object of the invention is the provision of a simple latch adapted to be actuated by the foot of a person from either side of the gate or door, and which latch includes means for forcibly swinging the gate open upon actuation thereof for releasing the gate.

A still further object of the invention is the provision of a springless gate or door latch including means forcibly swinging the gate open upon actuation of the latch for releasing the gate, and which latch further includes a weight for restoring the latch and the means for swinging the gate back to a position for latching the gate when the latter swings to closed position and for again swinging the gate open.

Other objects and advantages will appear in the following description and in the drawings.

In the drawings, Fig. 1 is a perspective view of a fragment of the gate (along the edge opposite its hinges) showing the latch bar and one of the elements employed for swinging the gate open.

Fig. 2 is a perspective view of a fragment of the gate jamb showing the catch and the means for releasably holding the latch bar and for swinging the gate.

Fig. 3 is an elevational view showing the latch elements from the opposite side of the latch supporting plate seen in Fig. 2.

In Fig. 2 a fragment of the latch bar and a portion of the element that cooperates with the catch are indicated in normal position when the gate is closed. Figs. 1 and 2 as seen on the sheet are shown in generally the same positions relative to each other as they would be in actual use, except that they are separated for clarity in about the same manner as though Figs. 1 and 2 were considered together as an exploded view of the latch bar and catch.

In detail, the latch bar comprises a horizontally extending bar 1 that is pivotally secured by a horizontal pivot 2 to a plate 3. The pivot 2 is at one end of bar 1 and the opposite end 4 projects outwardly of the edge of plate 3. A keeper 5 is secured to plate 3 and extends over the end of bar 1 adjacent its outer end 4 for supporting the bar generally horizontal while permitting upward movement of said end 4.

2

The plate 3 is adapted to be secured by any suitable means, such as screws or bolts 6 to any desired part of the gate, but along the free edge of the latter that is opposite the hinges (not shown), so that the outer end 4 of the latch bar will project outwardly of said free edge.

In Fig. 1 the plate 3 is secured to the lower horizontal strip 7 to which the pickets 8 forming the gate are secured. The outer end 4 of bar 1 is laterally offset relative to the main body of the bar to place the said outer end in a more desirable position for engagement by the catch that is on the jamb, but said offset is not essential and if the plate 3 were secured on pickets 8 the bar 15 could be straight.

The catch elements are carried on a plate 9 that is adapted to be secured to the jamb 10 of the gate by any suitable means, such as screws 11. This plate is adapted to be secured on the face of the jamb that faces the gate.

A horizontally extending retainer strip 15 is secured to plate 9 in spaced opposed relation to the side of said plate facing the gate. This strip 15 is formed integrally with a horizontally disposed shelf 16 along its lower edge that extends to plate 9 and a downward projection 17 that extends downwardly from shelf 16 and that is secured to plate 9 by bolts or screws 18.

Retainer strip 15 has a vertically extending end edge 20 at one end and against which the outer end 4 of the latch bar 1 is adapted to engage when the gate is closed. Said end of the latch bar is indicated at 4 in Fig. 2 in dot-dash lines.

The upper edge 21 of the retainer strip extends slantingly downwardly and convergently relative to shelf 16 in direction away from the end edge 20.

Extending longitudinally of shelf 16 over the latter and between plate 9 and retainer strip 15 is a horizontally extending arm 25. This arm 25 extends beyond the end edge 20 of retainer strip 15 and has an upward projection 26 formed integrally therewith. This projection preferably curves slightly in direction away from the retainer strip at its upper end 27 and said projection constitutes a gate actuating means for forcibly swinging the gate open, as will be later described. At this point it is to be noted that the outer end 4 of the latch bar 1 extends across the projecting end of arm 25 between edge 20 of retainer plate 15 and the projection.

The arm 25 is pivoted intermediate its ends on a horizontal pivot 28 that extends through the convergent end of strip 15, and said arm

extends past said pivot in direction away from said convergent end of strip 15 terminating in the form of a flat pedal 30.

This projecting end 30 of arm 25 is adjacent one of the lateral sides of jamb 10 that is adjacent the side to which plate 9 is secured. Upon depressing the pedal or end 30, it will be seen that the opposite end of said arm will be elevated thus lifting the end 4 of the latch bar clear of the retainer strip 15 and at the same time the upper end 27 of projection 26 will swing generally laterally in direction across the plate 9 toward pedal 30.

Rigidly secured to the gate above the latch bar is a horizontally extending strip 31 that projects at one end 32 outwardly of the same edge of the gate as the end 4 of the latch bar. This projecting end 32 may be rounded and is adapted to extend across the side of the upper end 27 of projection 26 in the path of travel of the latter when it is swung by depression of pedal 30. Normally the projection 32 is spaced from the end 27 of projection 27 a slight distance, but just as soon as latch end 4 clears the upper edge of strip 15 the projection 32 will be engaged by end 27 and continued movement of the end 27 will forcibly swing the gate open.

A clevis 33 may be swingably secured on projection 32 for swinging into engagement with the end 27 when the gate is closed so that the end 27 extends into the clevis for locking the end 27 against swinging a sufficient distance to permit latch end 4 from clearing the strip 15. However, when the clevis is in the position seen in Fig. 1 it is inoperative for locking the gate closed.

A strip 35 parallel with arm 25 extends across the opposite side of plate 9 from arm 25 and into a recess 36 cut in the jamb 10. The end of strip 35 that is about opposite the end of arm 25 that carries projection 26 is pivotally secured to plate 9 by pivot 37. The other end of strip 35 is adjacent the pedal 30 and is bent at right angles toward arm 25 to form an end portion 38 extending across the edge of plate 9. The terminating end of portion 38 is preferably reduced to form a cylindrical pin 39 that extends through a horizontal slot 40 that is formed in arm 25.

A second arm 42 is spaced below strip 35 and is on the same side of plate 9 as said strip. This arm is pivoted by pivot 43 to plate 9 adjacent the edge of said plate across which the portion 38 of said strip extends.

The other end of arm 42 projects from the side of jamb 10 opposite the side from which pedal 30 projects, and said other end terminates in a pedal 44 that is similar to pedal 30. A link 45 is pivotally connected at one end by pivot 46 to strip 35 at a point intermediate the pivot 37 and portion 38 but nearer the former. The opposite end of link 45 is pivoted at 47 to arm 42. Thus, upon depressing the pedal 44 the arm 25 will be actuated in exactly the same manner as though pedal 30 were depressed and the end 4 of the latch bar 1 will clear strip 15 and projection 26 will forcibly swing the gate open through engagement between end 27 and the projecting end 32 of strip 31.

In order to restore the catch elements which comprise arms 25, 42 and their associated members to the position shown in Fig. 2 after each actuation thereof, a weight 50 is secured to the end of arm 25 below the upward projection 26. This weight is rigid with the arm 25 and in operation easily and freely restores the catch elements to the position shown in Fig. 2.

After the gate has been swung to open position, the end 4 of the latch bar will slide upwardly over the inclined edge 21 of strip 15 when the gate swings back to closed position, and said end 4 will automatically drop into gate latching position as soon as it clears said upper edge at end edge 20.

It is to be understood that the references to a "gate" and the other details of the description are not intended to be restrictive of the invention, but are merely illustrative of one form thereof. The invention is applicable to a door, and instead of being placed at the lower portion of a gate, as shown in the drawing, so as to be actuated by the foot of a person, it may be placed higher up for manual operation. Foot operation is preferable since a person may readily open the gate when the hands are occupied by carrying packages or other articles.

I claim:

1. A latch including a horizontally extending latch bar pivoted at one end for upward swinging of the opposite end, a catch comprising a base element and a pair of horizontally opposed members adjacent thereto, said opposite end of said latch bar being adapted to extend over said element and between said members when said latch bar is secured on a gate and the catch is secured on the jamb and when said gate is closed, means for so securing said latch bar and said catch on such gate and jamb respectively, means supporting said element for upward movement to lift said latch bar a distance for clearing the upper end of one of said opposed members to thereby permit swinging of such gate in one direction, depressible means connected with said element for causing said movement, gate actuating means connected with said depressible means supported for generally lateral movement in said one direction substantially simultaneously with said upward movement of said element, means adapted to be secured to such gate for engagement by said gate actuating means upon said lateral movement of the latter for forcibly swinging said gate in said one direction upon actuation of said depressible means for elevating said element and said latch bar.

2. A latch including a horizontally extending latch bar pivoted at one end for upward swinging of the opposite end, a catch comprising a base element and a pair of horizontally opposed members adjacent thereto, said opposite end of said latch bar being adapted to extend over said element and between said members when said latch bar is secured on a gate and the catch is secured on the jamb and when said gate is closed, means for so securing said latch bar and said catch on such gate and jamb respectively, means supporting said element for upward movement to lift said latch bar a distance for clearing the upper end of one of said opposed members to thereby permit swinging of such gate in one direction, depressible means connected with said element for causing said movement, gate actuating means connected with said depressible means supported for generally lateral movement in said one direction substantially simultaneously with said upward movement of said element, means adapted to be secured to such gate for engagement by the latter for forcibly swinging said gate in said one direction upon actuation of said depressible means for elevating said element and said latch bar, gravity actuated means connected with said depressible means and with said element for automatically elevating said depressible

means and for lowering said element after each depression of the former.

3. A latch including a horizontally extending latch bar pivoted at one end for upward swinging of the opposite end, a catch comprising a base element and a pair of horizontally opposed members adjacent thereto, said opposite end of said latch bar being adapted to extend over said element and between said members when said latch bar is secured on a gate and the catch is secured on the jamb and when said gate is closed, means for so securing said latch bar and said catch on such gate and jamb respectively, means supporting said element for upward movement to lift said latch bar a distance for clearing the upper end of one of said opposed members to thereby permit swinging of such gate in one direction, compressible means adapted to project laterally from opposite sides of such gate and jamb for actuation from either side of said gate and connected with said element for causing said movement, gate actuating means connected with said element and movable generally laterally in said one direction upon said upward movement of said element, means adapted to be secured to such gate for engagement by said gate actuating means upon said lateral movement of the latter for forcibly swinging said gate in said one direction upon actuation of said compressible means for elevating said element and said latch bar.

4. A latch including a horizontally extending latch bar pivoted at one end for upward swinging of the opposite end, a catch including a horizontally extending arm having a vertically extending projection at one end rigid therewith, means pivotally supporting said arm at a point intermediate its ends for upward swinging of said one end and for generally lateral swinging of said projection in one direction upon depression of the opposite end of said arm, separate means for securing said latch bar on a gate and for securing said arm on the jamb of such gate with said opposite end of said bar extending transversely across said arm closely adjacent said projection, and means adapted to be secured to such gate above said latch bar for engagement by said projection upon said lateral swinging of the latter for forcibly swinging said gate in said one direction when the said opposite end of said arm is depressed.

5. A latch including a horizontally extending latch bar pivoted at one end for upward swinging of the opposite end, a catch including a horizontally extending arm having a vertically extending projection at one end rigid therewith, means pivotally supporting said arm at a point intermediate its ends for upward swinging of said one end and for generally lateral swinging of said projection in one direction upon depression of the opposite end of said arm, separate means for securing said latch bar on a gate and for securing said arm on the jamb of such gate with said opposite end of said bar extending transversely across said arm closely adjacent said projection, and means adapted to be secured to such gate above said latch bar for engagement by said projection upon said lateral swinging of the latter for forcibly swinging said gate in said one direction when the said opposite end of said arm is depressed, a weight connected with said arm for automatically swinging said projection back to vertically extending position after said lateral movement.

6. A latch including a horizontally extending latch bar pivoted at one end for upward swing-

ing of the opposite end, a catch including a horizontally extending arm having a vertically extending projection at one end rigid therewith, means pivotally supporting said arm at a point intermediate its ends for upward swinging of said one end and for generally lateral swinging of said projection in one direction upon depression of the opposite end of said arm, separate means for securing said latch bar on a gate and for securing said arm on the jamb of such gate with said opposite end of said bar extending transversely across said arm closely adjacent said projection, and means adapted to be secured to such gate above said latch bar for engagement by said projection upon said lateral swinging of the latter for forcibly swinging said gate in said one direction when the said opposite end of said arm is depressed, said opposite end of said arm extending horizontally outwardly of one side of said gate and jamb when said latch bar and said catch are so secured on said gate and jamb, compressible means connected with said arm and projecting from the opposite side of such gate and jamb, and means connecting said compressible means with said arm for causing downward movement of the said opposite end of said arm upon depression of said compressible means whereby said gate may be swung open from either side of said gate by similar operations.

30 7. A latch including a horizontally extending latch bar pivoted at one end for upward swinging of the opposite end, a catch including a horizontally extending arm having a vertically extending projection at one end rigid therewith, means pivotally supporting said arm at a point intermediate its ends for upward swinging of said one end and for generally lateral swinging of said projection in one direction upon depression of the opposite end of said arm, separate means for securing said latch bar on a gate and for securing said arm on the jamb of such gate with said opposite end of said bar extending transversely across said arm closely adjacent said projection, and means adapted to be secured to such gate above said latch bar for engagement by said projection upon said lateral swinging of the latter for forcibly swinging said gate in said one direction when the said opposite end of said arm is depressed, said opposite end of said arm being adjacent the ground for actuation by the foot of a person, and means adjacent said projection in opposed relation to said projection for securing said latch bar against lateral movement until depression of said arm.

55 8. A latch including a horizontally extending latch bar pivoted at one end for upward swinging of the opposite end, a catch including a horizontally extending first arm, a plate, means pivotally supporting said arm to said plate at a point intermediate the ends of said arm for upward swinging of one end thereof upon depression of the other end, separate means for securing said latch bar on a gate and for securing said plate on the jamb with said opposite end of said bar extending over said one end of said arm at substantially right angles to the latter, a second arm pivotally secured to the side of said plate opposite said first arm, said first arm and said second arm projecting from opposite edges of said plate and from opposite sides of said jamb when the plate is secured to the jamb, means connecting said first arm and said second arm for simultaneous downward movement of their projecting ends and upward movement of said one end of said first arm upon depression of either

of said projecting ends, a weight connected with said first arm adjacent its said one end for automatically elevating said projecting ends to normal predepressed position after depression thereof and release of said arms, gate actuating means rigidly connected with said first arm for lateral swinging upon depression thereof, and means adapted to be rigidly secured to said gate in a position for engagement by said gate actuating means for forcible movement in one lateral direction for swinging said gate in said direction.

9. A latch including a horizontally extending latch bar pivoted at one end for upward swinging of the opposite end, a catch including a horizontally extending first arm, a plate, means pivotally supporting said arm to said plate at a point intermediate the ends of said arm for upward swinging of one end thereof upon depression of the other end, separate means for securing said latch bar on a gate and for securing said plate on the jamb with said opposite end of said bar extending over said one end of said arm at substantially right angles to the latter, a second arm pivotally secured to the side of said plate opposite said first arm, said first arm and said second arm projecting from opposite edges of said plate and from opposite sides of said jamb when the plate is secured to the jamb, means connecting said first arm and said second arm for simultaneous downward movement of their projecting ends and upward movement of said one end of said first arm upon depression of either of said projecting ends, a weight connected with said first arm adjacent its said one end for automatically elevating said projecting ends to normal predepressed position after depression thereof and release of said arms, gate actuating means rigidly connected with said first arm for lateral swinging upon depression thereof, and means adapted to be rigidly secured to said gate in a position for engagement by said gate actuating means for forcible movement in one lateral direction for swinging said gate in said direction, stationary means on said plate for securing said latch bar against movement laterally in said one direction when said one end of said first arm is in its lowered position before depression of its other end.

10. A latch including a horizontally extending latch bar pivoted at one end for upward swinging of the opposite end, a catch including a horizontally extending first arm, a plate, means pivotally supporting said arm to said plate at a point intermediate the ends of said arm for upward swinging of one end thereof upon depression of the other end, separate means for securing said latch bar on a gate and for securing said plate on the jamb with said opposite end of said bar extending over said one end of said arm at substantially right angles to the latter, a second arm pivotally secured to the side of said plate opposite said first arm, said first arm and said second arm projecting from opposite edges of said plate and from opposite sides of said jamb when the plate is secured to the jamb, means connecting said first arm and said second arm for simultaneous downward movement of their projecting ends and upward movement of said one end of said first arm upon depression of either of said projecting ends, a weight connected with said first arm adjacent its said one end for automatically elevating said projecting ends to normal predepressed position after depression thereof and release of said arms, gate actuating means rigidly connected with said first arm for lateral swinging upon depression thereof, and means adapted to be rigidly secured to said gate in a position for engagement by said gate actuating means for forcible movement in one lateral direction for swinging said gate in said direction, means for releasably locking said first and second arms against movement thereof.
